UNITED STATES PATENT OFFICE

ANTONIO V. SIMONE, OF CROTON ON HUDSON, NEW YORK

SHAVING COMPOSITION

No Drawing.

Application filed September 29, 1928. Serial No. 309,355.

This invention relates to shaving compound, and has for an object the production of a composition for use as a shaving compound whose lather will tend to soften the beard of the user and produce a soothing effect for the skin, resulting in what is regarded as an ideal condition for a compound of this character.

It is a further object of this invention to produce a shaving compound of the character indicated which is comparatively inexpensive and one that has proven efficient and satisfactory.

With the foregoing and other objects in view, the invention consists in the ingredients and substantially in the proportions set forth.

In carrying the invention into practice, I employ soap suitable for shaving, boric acid and phenolphthalein and preferably the ingredients are employed in the following proportions, viz:

Shaving soap 10 parts; boric acid 2 parts; and phenolphthalein 1 part.

It has also been found in practice that a composition consisting of soap suitable for shaving commingled with glycyrrhiza produces advantageous results and specifically the ingredients have been used in the following proportions, viz: shaving soap 12 parts; glycyrrhiza 1 part.

The composition can be prepared for use either as a cream or in solid form in cakes or sticks, or it may be powdered.

I claim:

35 A shaving composition consisting of shaving soap 12 parts and glycyrrhiza 1 part.

ANTONIO V. SIMONE.
